PROCESS FOR PRODUCING PARAFFINIC OILS

Frederick E. Frey, Bartlesville, Okla., Paul V. McKinney, Pittsburgh, Pa., and William H. Wood, Cleveland, Ohio, assignors to Phillips Petroleum Company, a corporation of Delaware

Original application June 27, 1936, Serial No. 87,790. Divided and this application September 5, 1940, Serial No. 355,528.

13 Claims. (Cl. 196—10)

This invention relates to the manufacture of paraffinic and saturated hydrocarbon oils, and more specifically to the production of paraffinic oils suitable for motor fuel by catalytic synthesis from hydrocarbons of lower molecular weight.

This application is a division of our copending application, Serial No. 87,790, filed June 27, 1936, entitled Process for producing paraffinic oils, now Patent 2,233,363, issued February 25, 1941.

The conversion of normally gaseous olefins into valuable hydrocarbons of higher molecular weight, suitable for motor fuels, has been effected by heat and pressure, and the use of elevated pressures effecting rapid reaction and nearly complete conversion at temperatures below the pyrolysis range. The polymerization may also be effected with the aid of suitable catalysts at temperatures lower than those required for the purely thermal conversion. The hydrocarbons of higher molecular weight which result, are, in either case, composed of varying proportions of hydrocarbons of several types, a large proportion being olefinic or unsaturated. Such olefinic polymers may be converted into oils of saturated type by means of hydrogenation preferably of the non-destructive type.

The present invention is an improvement of the invention set forth in Frey's application Serial No. 731,920, filed June 22, 1934, which issued May 21, 1935, as Patent 2,002,394, and also is an improvement of the invention set forth in Frey's application Serial No. 12,981 filed March 25, 1935, which was copending with said application of which this is a division, which is a continuation-in-part of the aforesaid application and which issued January 4, 1938, as Patent No. 2,104,296.

It is an object of the present invention to effect a process for the formation of predominantly saturated oils at relatively low temperatures, below those required for producing such oils by thermal means, or at appreciably lower pressures, with resultant saving in plant construction and operating expense, by effecting catalytically the polymerization reactions which involve the direct union of paraffins and olefins of lower molecular weight than the oils to be produced.

A further object of this invention is to provide a process for the production of oils of essentially saturated type without the step of hydrogenating partly olefinic polymer oils.

A still further object is to provide a process for the conversion of paraffins of low molecular weight into oils of higher molecular weight without the intermediate conversion into simple ole-

finic hydrocarbons prior to effecting conversion into oils.

Other objects will be apparent upon a further consideration of the following description of this invention.

The normally gaseous olefins, ethylene, propylene, and the butylenes may be converted in the process, constituting our invention, together with propane and butane which are normally gaseous, and pentanes. The conversion of pentanes, and paraffins of somewhat higher molecular weight, is desirable in circumstances in which their volatility is undesirably high. It will be understood that by paraffins of low molecular weight is meant those which may yield by union with olefins, oils boiling within the gasoline range.

We have found that the union of paraffins with olefins to produce saturated hydrocarbons of higher molecular weight can be effected with known polymerization catalysts under new and appropriate conditions and in novel processes which will be presently described. Catalysts effective for the reaction are aluminum chloride chemically combined with an equimolar quantity, more or less, of lithium, sodium, calcium, or potassium chloride, and the corresponding double compounds in which chlorine is replaced by bromine. Other modifying agents added to aluminum chloride or bromide may also be employed. Zinc chloride, zinc bromide, hydrous alumina, and hydrous alumina deposited on or combined with hydrous silica, are likewise effective for catalyzing the reaction. The catalyst is conveniently used in granular form or disposed on an inert granular support. We have found that oils of a saturated type may be produced by reacting together a mixture of paraffins with olefins, provided the ratio of olefins to paraffin is low in the mixture subjected to the action of the catalyst, and our process provides means whereby extensive and practical conversion may be obtained by passing the hydrocarbon stream into contact with the catalyst while maintaining a reaction temperature and while adding olefin in small proportion a plurality of times in the course of the reaction, addition of olefin taking place prior to contact with the catalyst in each addition, whereby added olefin is consumed prior to each subsequent addition of additional olefin. The concentration of olefin present throughout the reaction is in this way maintained at a low value, and the paraffinic reactants at a high value. The temperature of the reaction is somewhat higher than the optimum for the familiar

catalytic polymerization involving union of olefin with olefin, and will vary from 100° to about 400° C., the lower temperatures being most favorable for the utilization of the modified aluminum halide catalysts, and the higher temperatures more favorable for zinc halide, and alumina associated with silica and hydrated phosphorus pentoxide. We have found that elevated pressures are required for obtaining efficient reaction in which paraffin takes part, and pressures in excess of 100 pounds per square inch are employed, the reaction proceeding more efficiently in most cases as the pressure increases up to about 3000 pounds per square inch, though higher pressures may usually be used without adverse effect on the reaction. Pressures of 400 to 2500 pounds per square inch are preferable in most cases. With high olefin contents, exceeding 30%, the paraffins enter into reaction to only a limited degree, and the oils produced are largely of the familiar unsaturated type. Accordingly, we maintain olefin concentration below 20%, and preferably below 10%, in order to obtain efficient cooperative reaction of paraffins and olefins. Olefin concentration in the paraffinic reactants as low as 0.5% may be maintained economically in the presence of the catalyst by making small olefin additions a sufficiently great number of times in the course of the reaction. The time of residence in the catalyst zone will vary with the manner of disposing catalyst in the reaction chamber and with the particular catalyst employed as will also the temperature of reaction, and both can be readily determined by experiment. The oils produced by this process are predominantly paraffinic, containing 20% or less of unsaturated hydrocarbons and distilled almost wholly in the gasoline range, that is, below 225° C.

Figure 1 illustrates diagrammatically one form of apparatus for effecting the present process, and, Figure 2 illustrates diagrammatically a modified form of apparatus for effecting the process.

The operation of the process constituting this present invention will be readily understood from a consideration of Figure 1 of the attached drawings, and the following description relative thereto.

A stream of paraffinic hydrocarbons of low molecular weight is charged to the apparatus illustrated diagrammatically in Figure 1 by introducing the same by way of conduit 10 through which the hydrocarbons pass to the pump 11 and are thereby forced to the heater 12 wherein they are brought to a reaction temperature. The desired degree of heat may be maintained in the heater 12 by any suitable heating means, such as heating coils which may be provided with a feed pipe 13 and an outlet pipe 14.

From the heater 12 the stream of paraffinic hydrocarbons flows through the conduit 15 to the plurality of catalyst chambers 16, 17, 18, 19, 20, and 21 which are arranged in series. Portions of the catalyst chambers 16 and 17, 18 and 19, and 20 and 21 are connected by the conduits 22, 23, and 24 respectively; while other portions of the catalyst chambers 17 and 18, and 19 and 20 are connected by the conduits 25 and 26 respectively. A conduit 27 connects conduit 24 with conduit 15 adjacent the chamber 16, and also connected to the conduit 27 are the conduits 28, 29 and 30 which connect with conduits 22, 23 and 24 respectively, and the conduits 31 and 32 which connect with the conduits 25 and 26 respectively.

Normally gaseous olefins are introduced into the system through conduit 33 and are forced by the pump 34 to the conduit 27 through which the normally gaseous olefins flow to the conduits 28, 29 and 30 to be introduced by conduits 22, 23 and 24 into the catalytic chambers 17, 19, and 21 respectively. From conduit 27 the olefins also flow through conduits 31, and 32 into the conduits 25 and 26 to be introduced into the catalyst chambers 18 and 20. Conduit 27 also conduits olefins directly to conduit 15, from which they flow into the catalyst chamber 16.

Thus it will be appreciated that a reaction between the paraffinic hydrocarbons introduced into the process by way of conduit 10, and the olefinic hydrocarbons introduced by way of conduit 33, takes place in the several catalyst chambers 16, 17, 18, 19, 20 and 21 through which the reacting paraffinic and olefinic hydrocarbons flow in series. The reacting paraffinic and olefinic hydrocarbons after reaching the last catalyst chamber 21 pass therefrom through the conduit 35 into a separator 36 wherein oils of a higher molecular weight are separated and discharged from the process through the conduit 37 controlled by the valve 38.

Unreacted paraffins of low molecular weight and containing a small amount of olefin will pass from the separator 36 through the conduit 39, and will be forced by the pump 40 into the conduit 15 to be passed to the first catalyst chamber 16 and the succeeding ones as described.

The paraffins of low molecular weight most suitable for the process, namely propane, butane, pentanes and somewhat heavier paraffins may contain paraffins of lower molecular weight, and may be derived from petroleum, natural gas, or cracking still gases and other sources. Olefins may be derived from cracking still gases, from pyrolysis of petroleum distillates and gases, and from dehydrogenation of ethane, propane, and butane. The product of catalytic partial dehydrogenation, containing unconverted paraffin together with the corresponding olefin is particularly suitable for conversion in our process, since both paraffin and olefin are present. Such a mixture of paraffin and olefin may be introduced through conduit 33 of Figure 1 as olefinic stock. The olefin depleted paraffin recovered in separator 36 may be returned through conduit 38 to serve as the paraffinic reactant, and unconverted paraffins in excess are discharged through conduit 41 by opening valve 42 and thereafter may be subjected to partial dehydrogenation and returned once more to the process by any suitable manner not shown. This process is most advantageously applied to the conversion of propane and butane. The reacting of an individual paraffin with an individual olefin yields an oil of relatively simple composition predominating in saturated hydrocarbons whose molecular weight is the sum of that of the paraffin and the olefin.

Example

Isobutane was passed at 3,000 pounds per square inch pressure and 200° C. through a tube containing 10 cc. of granular pumice (14-20 per inch mesh) coated with a catalyst prepared by melting together equimolar quantities of sodium chloride and anhydrous aluminum chloride. A volume of isobutylene equal to 10% of the isobutane was divided into four streams and introduced into the catalyst tube at four equidistant points, the rate of flow of the hydrocarbon being such that the time of passage through the cata-

lyst zone occupied 10 minutes. The effluents had the following composition:

	Weight per cent
Methane	0.2
Butane	81.4
Butylene	1.0
Pentanes	2.8
Hexanes	1.0
Heptanes and octanes	11.8
Heptylenes and octylenes	0.5
Higher hydrocarbons	1.3
Total	100.0

As the analysis shows, the quantity of isobutane consumed was approximately equal to the isobutylene consumed. The oils formed were almost wholly paraffinic in character and predominated in material distilling in the heptane-octane range.

Figure 2 illustrates diagrammatically a modified apparatus for effecting the present invention, and herein hydrocarbons, consisting of olefins and paraffins, which are to be reacted, enter the process together with each other through the conduit 50 and are forced by the pump 51 through the conduit 52 to the reaction chamber 53 wherein the hydrocarbons, comprising paraffins and olefins, are brought into contact with a catalyst suitable for effecting the desired polymerization reaction.

The reacted hydrocarbons are discharged from the chamber 53 into the conduit 54 and are divided into two streams, one of which flows through valve 55A into conduit 55 and is forced by pump 56 through valve 55B back into conduit 52 to be reintroduced into the reaction chamber 53. The other stream of reacted hydrocarbons flows through valve 57A and into conduit 57 passing into the separator 58 wherein the hydrocarbons of higher molecular weight produced by the reaction are separated from the lighter hydrocarbons and discharged through conduit 59 controlled by valve 60.

Any unreacted gases will be predominantly paraffinic and may be discharged through conduit 61, and may be reacted with additional olefin or put to any other desired use.

However, it is to be understood that it may not always be desirable, or necessary, to recycle the reacted hydrocarbons from chamber 53 back through conduits 55 and 52 for reprocessing in the reaction chamber, so therefore when desired, or conditions demand, the valves 55A and 55B, which are interposed in conduit 55, may be closed.

Or it may be desirable, or necessary, to recycle the reacted hydrocarbons from chamber 53 back through the conduits 55 and 52 to the chamber again with only a minimum amount of the reacted hydrocarbons passing directly from the chamber 53 through conduits 54 and 57 to the separator 58, in such a case the valve 57A may be set at any desired partially closed position to limit the flow of the reacted hydrocarbons directly from chamber 53 to separator 58.

From the foregoing it should appear obvious that by control of valves 55A and 55B, and valve 57A the flow of the reacted hydrocarbons from the chamber 53 to the separator 58, or the recycling of these hydrocarbons back through the chamber 53 can be readily controlled and regulated.

We claim:

1. A continuous process for reacting paraffins

of low molecular weight with normally gaseous olefins to produce predominantly paraffinic oils in the motor fuel boiling range and of higher molecular weight, which comprises bringing the paraffins into contact with a polymerization catalyst of the group consisting of aluminum chloride combined with a substantial proportion of an alkali halide and aluminum bromide combined with a substantial proportion of an alkali halide in a reaction zone for a suitable reaction period while maintaining a reaction temperature between 100° and 400° C. and a pressure of at least 100 pounds per square inch, introducing normally gaseous olefins to the reaction zone a plurality of times during the reaction period while maintaining the concentration of added olefin present in the reacting hydrocarbons below 20 per cent, withdrawing the reacted hydrocarbons from the reaction zone and separating therefrom a hydrocarbon fraction containing the predominantly paraffinic oils in the motor fuel boiling range so produced.

2. A continuous process for reacting paraffins of low molecular weight with normally gaseous olefin hydrocarbons to produce predominantly paraffinic oils of high molecular weight in the motor fuel boiling range, which comprises passing a stream of hydrocarbons comprised of paraffins of low molecular weight in which normally gaseous olefin hydrocarbons are dispersed through a reaction zone at a temperature between 100° and 400° C. and a pressure greater than 100 pounds per square inch, and in the presence of a polymerization catalyst of the group consisting of aluminum chloride combined with a substantial proportion of an alkali halide and aluminum bromide combined with a substantial proportion of an alkali halide, for a period of time such that reaction takes place consuming paraffin hydrocarbons and said olefin hydrocarbons and dispersing normally gaseous olefin hydrocarbons in said stream of hydrocarbons during said period of time in such a manner that the concentration of unreacted unsaturated hydrocarbons present in the mixture does not exceed 20 per cent by weight of the total hydrocarbon stream and separating from at least a portion of the effluent of said reaction zone a hydrocarbon fraction comprising paraffinic oils in the motor fuel boiling range.

3. A continuous process for reacting paraffins of low molecular weight with normally gaseous olefin hydrocarbons to produce predominantly paraffinic oils of higher molecular weight in the motor fuel boiling range which comprises passing a stream of hydrocarbons comprised of paraffins of low molecular weight in which normally gaseous olefin hydrocarbons are dispersed, while at a reaction temperature between 100° and 400° C. and a pressure greater than 100 pounds per square inch, through a reaction zone in the presence of a polymerization catalyst of the group consisting of aluminum chloride combined with a substantial proportion of an alkali halide and aluminum bromide combined with a substantial proportion of an alkali halide, for a period of time such that reaction takes place consuming paraffin hydrocarbons and said olefin hydrocarbons, passing a portion of the effluents of said reaction zone to be mixed with the hydrocarbon stream entering said zone and separating from another portion of said effluents predominantly paraffinic oils of higher molecular weight in the motor fuel boiling range so produced.

4. In a continuous process for producing predominantly paraffinic hydrocarbons of high molecular weight from paraffins and olefins of lower molecular weight, the steps which comprise maintaining a stream of predominantly paraffinic hydrocarbons in independent cyclic circulation through a reaction zone containing a polymerization catalyst of the group consisting of aluminum chloride combined with a substantial proportion of an alkali halide and aluminum bromide combined with a substantial proportion of an alkali halide, and wherein a reaction temperature between 100° and 400° C. and a pressure between 100 and 3000 pounds per square inch are maintained and wherein a catalyzed reaction takes place consuming paraffin and added olefin hydrocarbons, introducing into said stream an olefin-containing hydrocarbon mixture such that the concentration of added, unreacted olefins does not exceed 20 per cent by weight of the total mixture local to the point of introduction, withdrawing from the said stream a portion thereof and separating therefrom predominantly paraffinic hydrocarbons of higher molecular weight.

5. In a continuous process for producing predominantly paraffinic hydrocarbons of higher molecular weight from paraffins and olefins of lower molecular weight the steps which comprise maintaining a predominantly paraffinic hydrocarbon mixture in continuous circulation in an endless circulatory cycle which contains a reaction zone containing a polymerization catalyst of the group consisting of aluminum chloride combined with a substantial proportion of an alkali halide and aluminum bromide combined with a substantial proportion of an alkali halide, and a zone of hydrocarbon introduction, adding a hydrocarbon mixture containing paraffins of low molecular weight having at least three carbon atoms per molecule and olefin hydrocarbons at the zone of hydrocarbon introduction thereby producing a hydrocarbon mixture such that the concentration of unreacted added olefin is between 0.5 and 20 percent by weight of the total hydrocarbon mixture, passing the mixture to said reaction zone wherein a catalyzed reaction takes place consuming paraffins and olefins and forming paraffin hydrocarbons and maintaining therein a reaction temperature between 100° and 400° C. and a pressure in excess of 100 pounds per square inch, passing the reacted mixture back to the zone of hydrocarbon introduction thus completing the endless circulatory cycle, withdrawing at some point in the cycle a portion of the mixture and separating therefrom predominantly paraffinic hydrocarbons of higher molecular weight.

6. A continuous process for reacting paraffins of low molecular weight with normally gaseous olefin hydrocarbons to produce predominantly paraffinic oils of high molecular weight in the motor fuel boiling range, which comprises passing a stream of hydrocarbons comprised of paraffins of low molecular weight in which normally gaseous olefin hydrocarbons are dispersed through a reaction zone at a temperature between 100° and 400° C. and a pressure greater than 100 pounds per square inch, and in the presence of aluminum chloride combined with a substantial proportion of an alkali halide, for a period of time such that reaction takes place consuming paraffin hydrocarbons and said olefin hydrocarbons and dispersing normally gaseous olefin hydrocarbons in said stream of hydrocar-

5 carbons during said period of time in such a manner that the concentration of unreacted unsaturated hydrocarbons present in the mixture does not exceed 20 per cent by weight of the total hydrocarbon stream and separating from at least a portion of the effluent of said reaction zone a hydrocarbon fraction comprising paraffinic oils in the motor fuel boiling range.

7. A continuous process for reacting paraffins of low molecular weight with normally gaseous olefin hydrocarbons to produce predominantly paraffinic oils of high molecular weight in the motor fuel boiling range, which comprises passing a stream of hydrocarbons comprised of paraffins of low molecular weight in which normally gaseous olefin hydrocarbons are dispersed through a reaction zone at a temperature between 100° and 400° C. and a pressure greater than 100 pounds per square inch, and in the presence of aluminum bromide combined with a substantial proportion of an alkali halide, for a period of time such that reaction takes place consuming paraffin hydrocarbons and said olefin hydrocarbons and dispersing normally gaseous olefin hydrocarbons in said stream of hydrocarbons during said period of time in such a manner that the concentration of unreacted unsaturated hydrocarbons present in the mixture does not exceed 20 per cent by weight of the total hydrocarbon stream and separating from at least a portion of the effluent of said reaction zone a hydrocarbon fraction comprising paraffinic oils in the motor fuel boiling range.

8. A continuous process for reacting paraffins of low molecular weight with normally gaseous olefin hydrocarbons to produce predominantly paraffinic oils of high molecular weight in the motor fuel boiling range, which comprises passing a stream of hydrocarbons comprised of paraffins of low molecular weight in which normally gaseous olefin hydrocarbons are dispersed through a reaction zone at a temperature between 100° and 400° C. and a pressure greater than 100 pounds per square inch, and in the presence of aluminum chloride combined with a substantial proportion of an alkali chloride, for a period of time such that reaction takes place consuming paraffin hydrocarbons and said olefin hydrocarbons and dispersing normally gaseous olefin hydrocarbons in said stream of hydrocarbons during said period of time in such a manner that the concentration of unreacted unsaturated hydrocarbons present in the mixture does not exceed 20 per cent by weight of the total hydrocarbon stream and separating from at least a portion of the effluent of said reaction zone a hydrocarbon fraction comprising paraffinic oils in the motor fuel boiling range.

9. A continuous process for reacting paraffins of low molecular weight with normally gaseous olefin hydrocarbons to produce predominantly paraffinic oils of high molecular weight in the motor fuel boiling range, which comprises passing a stream of hydrocarbons comprised of paraffins of low molecular weight in which normally gaseous olefin hydrocarbons are dispersed through a reaction zone at a temperature between 100° and 400° C. and a pressure greater than 100 pounds per square inch, and in the presence of aluminum bromide combined with a substantial proportion of an alkali bromide, for a period of time such that reaction takes place consuming paraffin hydrocarbons and said olefin hydrocarbons and dispersing normally gaseous olefin hydrocarbons in said stream of hydrocar-

bons during said period of time in such a manner that the concentration of unreacted unsaturated hydrocarbons present in the mixture does not exceed 20 per cent by weight of the total hydrocarbon stream and separating from at least a portion of the effluent of said reaction zone a hydrocarbon fraction comprising paraffinic oils in the motor fuel boiling range.

10. A continuous process for reacting paraffins of low molecular weight with normally gaseous olefin hydrocarbons to produce predominantly paraffinic oils of high molecular weight in the motor fuel boiling range, which comprises passing a stream of hydrocarbons comprised of paraffins of low molecular weight in which normally gaseous olefin hydrocarbons are dispersed through a reaction zone at a temperature between 100° and 400° C. and a pressure greater than 100 pounds per square inch, and in the presence of aluminum chloride combined with a substantial proportion of sodium chloride, for a period of time such that reaction takes place consuming paraffin hydrocarbons and said olefin hydrocarbons and dispersing normally gaseous olefin hydrocarbons in said stream of hydrocarbons during said period of time in such a manner that the concentration of unreacted unsaturated hydrocarbons present in the mixture does not exceed 20 per cent by weight of the total hydrocarbon stream and separating from at least a portion of the effluent of said reaction zone a hydrocarbon fraction comprising paraffinic oils in the motor fuel boiling range.

11. A continuous process for reacting paraffins of low molecular weight with normally gaseous olefin hydrocarbons to produce predominantly paraffinic oils of high molecular weight in the motor fuel boiling range, which comprises passing a stream of hydrocarbons comprised of paraffins of low molecular weight in which normally gaseous olefin hydrocarbons are dispersed through a reaction zone at a temperature between 100° and 400° C. and a pressure greater than 100 pounds per square inch, and in the presence of a polymerization catalyst of the group consisting of aluminum chloride combined with a substantial proportion of an alkali halide and aluminum bromide combined with a substantial proportion of an alkali halide, for a period of time such that reaction takes place consuming paraffin hydrocarbons and said olefin hydrocarbons and dispersing normally gaseous olefin hydrocarbons in said stream of hydrocarbons during said period of time in such a manner that the concentration of unreacted unsaturated hydrocarbons present in the mixture is between 0.5 and 10 per cent by weight of the total hydrocarbon stream and separating from at least a portion of the effluent of said reaction

zone a hydrocarbon fraction comprising paraffinic oils in the motor fuel boiling range.

12. A continuous process for reacting paraffins of low molecular weight with normally gaseous olefin hydrocarbons to produce predominantly paraffinic oils of high molecular weight in the motor fuel boiling range, which comprises passing a stream of hydrocarbons comprised of paraffins of low molecular weight in which normally gaseous olefin hydrocarbons are dispersed through a reaction zone at a temperature between 100° and 400° C. and a pressure greater than 100 pounds per square inch, and in the presence of a polymerization catalyst of the group consisting of aluminum chloride combined with a substantial proportion of an alkali halide and aluminum bromide combined with a substantial proportion of an alkali halide, for a period of time such that reaction takes place consuming paraffin hydrocarbons and said olefin hydrocarbons and dispersing normally gaseous olefin hydrocarbons in said stream of hydrocarbons during said period of time in such a manner that the concentration of unreacted unsaturated hydrocarbons present in the mixture is about 0.5 per cent by weight of the total hydrocarbon stream and separating from at least a portion of the effluent of said reaction zone a hydrocarbon fraction comprising paraffinic oils in the motor fuel boiling range.

13. A continuous process for reacting paraffins of low molecular weight with normally gaseous olefin hydrocarbons to produce predominantly paraffinic oils of high molecular weight in the motor fuel boiling range, which comprises passing a stream of hydrocarbons comprised of paraffins of low molecular weight in which normally gaseous olefin hydrocarbons are dispersed through a reaction zone at a temperature between 100° and 400° C. and a pressure greater than 100 pounds per square inch, and in the presence of aluminum chloride combined with a substantial proportion of an alkali chloride, for a period of time such that reaction takes place consuming paraffin hydrocarbons and said olefin hydrocarbons and dispersing normally gaseous olefin hydrocarbons in said stream of hydrocarbons during said period of time in such a manner that the concentration of unreacted unsaturated hydrocarbons present in the mixture is about 0.5 per cent by weight of the total hydrocarbon stream and separating from at least a portion of the effluent of said reaction zone a hydrocarbon fraction comprising paraffinic oils in the motor fuel boiling range.
